UNITED STATES PATENT OFFICE.

ISAAC C. NOBLE, OF NEW BEDFORD, MASSACHUSETTS.

WEIGHTING DEVICE FOR SPINNING MACHINES AND THE LIKE.

Application filed April 4, 1922. Serial No. 549,417.

To all whom it may concern:

Be it known that I, ISAAC C. NOBLE, a subject of the King of Great Britain, residing at New Bedford, in the county of Bristol and 5 State of Massachusetts, have invented new and useful Improvements in Weighting Devices for Spinning Machines and the like, of which the following is a specification.

This invention relates to devices such as 10 saddles and weight hooks for exerting pressure on the top rolls of spinning machines and the like.

It is a common expedient in the art to provide saddle or weight hooks of special construction for the purpose of minimizing friction and "chattering" in dead-weighting the top rolls, and this invention constitutes an improvement upon constructions heretofore known and used for the above mentioned 20 purpose.

In British patent to Hartcliffe, No. 2725 of 1855 there is disclosed a weight hook provided with a plurality of rotatable bearing members which rest upon the top roll and 25 exert pressure thereon. It has been found, however, that the construction disclosed in the patent, by reason of the forked formation of the end of the weight hook and the relation of the roller to the supporting portions of the weight hook, is unsatisfactory 30 due to the fact that grease and dirt collect between the rollers and the weight hook, and also because of the expense in constructing the weight hook as disclosed.

An object of this invention is to provide a 35 weight hook or saddle of simple and inexpensive construction provided with a plurality of rotatable bearing members adapted to engage the spinning machine rolls and 40 to maintain the weight hook and saddle member itself in spaced relation to the rolls, thereby minimizing friction and wear upon the rolls.

Another object of the invention is to arrange 45 the bearing rollers upon the saddle or hook in such a way that grease, dirt and other foreign matter will not collect upon the rolls and between the rolls and the weight hook or saddle strip.

A still further object of the invention is 50 to eliminate the necessity for frequent lubrication of the saddle or weight hook, as is required in connection with the use of saddles and weight hooks generally employed.

Referring to the drawings for a more 55 detailed description,

Fig. 1 represents a weight hook constructed according to the invention.

Fig. 2 is a top plan view of the structure shown in Fig. 1,

Fig. 3 is a cross sectional view taken on the line 3—3 of Fig. 1,

Fig. 4 is a view of a saddle adapted for the weighting of a plurality of rolls, and

Fig. 5 is a top plan of the saddle shown in Fig. 4.

Referring to the drawings for a more detailed description, 10 (Fig. 1) represents a weighting device comprising a strip having a hooked upper end 11 adapted to extend over the reduced hub or neck portion 12 of the roll of a spinning or like machine. The lower end of the strip may also be provided with a hook formation 12' adapted to be engaged by a weight 13, a portion 15 of which is shown in Fig. 1. In accordance with the invention, the strip is provided at its upper hooked end 11 with rotatable bearing members, in the present instance rollers 14, which are suitably supported upon studs 15 extending through the strip 10. The rollers are supported in pairs with the individual members of the pairs on the opposite sides of the strips. The pairs of rollers are arranged in spaced relation, 20 and the periphery of the rollers extends below the inner edge of the strip so that the strip is maintained spaced from the spinning roll hub.

By positioning the rollers upon opposite 25 sides of the strip the balance of the strip is at all times maintained, and it readily adjusts itself to the spinning machine roll. At the same time, an ordinary weight hook may be employed without specially constructing a hook, as is necessary in the device disclosed in the patent above referred to.

In order to prevent the accumulation of 30 grease between the rollers and the strip and the consequent retarding of the rotation of the rollers, the rollers are specially constructed so that there is a minimum area of contact between the inner side of the rollers and the strip. By reference to Fig. 3 it will be observed that the sides of the rollers adjacent the strip are tapered, as indicated at 16, and immediately adjacent the strip, around the studs 15, the rollers are of materially reduced diameter.

The outer faces 17 of the rollers are concaved; this prevents engagement of the ends

of the stud with the shoulder 12' of the spinning roll, and also presents but a small surface of the outer sides of the rollers to the ends of the leather bosses upon the roll. 5 It has been found that there is a tendency for the saddle or weight hook to move laterally longitudinally of the roll, and when there is but a small surface of the rollers to engage the ends of the bosses the friction is at a minimum. Moreover, in view of the fact that the bearing rollers are rotating in the same direction as the roll, the friction is far smaller than were the engaging portion of the saddle stationary with 15 respect to the roll.

By reference to Figs. 4 and 5 it will be noted that the weighting device takes the form of a saddle strip 10' having a weight 13' suspended therefrom. This strip is 20 adapted to weight a plurality of rolls, and is provided with four pairs of bearing rollers, two pair being used in association with each roll that is to be weighted. Of course, it will be understood that the number 25 of bearing rollers may be multiplied as desired. As in the arrangement shown in Fig. 1, the rollers are arranged upon studs 18 and are shaped in the same manner as the rollers shown in Fig. 3, this being clear 30 from an inspection of Fig. 5.

It should be understood that numerous modifications may readily be made in the construction of the weighting device shown in the accompanying drawings and herein 35 described in detail without departing from the scope of the invention, the invention not being limited to the particular type of bearing members or to the particular shape of the supporting strip shown and described.

40 I claim:

1. A weighting device for spinning machines and the like comprising a strip adapted to have a weighting member connected thereto, a plurality of pairs of rotatable bearing members on said strip, the individual members of the pairs being positioned on opposite sides of the strip, the bearing members being adapted to engage a spinning machine roll and to maintain 45 said strip spaced from the roll.

2. A weighting device for spinning machines and the like comprising a strip adapted to have a weighting member connected thereto, a plurality of pairs of roller bearing members on said strip, the individual 50

members of the pairs being positioned on opposite sides of the strip, the bearing members being adapted to engage a spinning machine

members of the pairs being positioned on opposite sides of the strip, the bearing members being adapted to engage a spinning machine roll and to maintain said strip spaced from the roll. 60

3. A weighting device for spinning machines and the like comprising a strip adapted to have a weighting member connected thereto, a plurality of pairs of roller bearing members on said strip, the individual members of the pairs being positioned on opposite sides of the strip, the bearing members being adapted to engage a spinning machine roll and to maintain said strip spaced from the roll, the sides of said 65 rollers adjacent the strip tapering from the periphery of the rollers. 70

4. A weighting device for spinning machines and the like comprising a strip adapted to have a weighting member connected thereto, a plurality of pairs of roller bearing members on said strip, the individual members of the pairs being positioned on opposite sides of the strip, the bearing members being adapted to engage a spinning machine roll and to maintain said strip spaced from the roll, the sides of said 75 rollers adjacent the strip tapering from the periphery of the rollers, and the other sides of the 80 rollers being concave. 85

5. A weighting device for spinning machines and the like comprising a strip adapted to have a weighting member connected thereto, a plurality of spaced studs extending through said strip, a pair of roller bearings positioned on each stud at opposite sides of the strip, said rollers being adapted to engage a spinning machine roll and to maintain the strip spaced from the roll. 90

6. A weighting device for spinning machines and the like comprising a strip adapted to have a weighting member connected thereto, a plurality of spaced studs extending through said strip, a pair of roller bearings positioned on each stud at opposite 95 sides of the strip, the inner sides of said rollers adjacent the strip being of substantially reduced diameter and the outer sides of the rollers being concave, said rollers being adapted to engage a spinning machine 100 roll and to maintain the strip spaced from the roll. 105

In testimony whereof I have hereunto set my hand.

ISAAC C. NOBLE.
